Attorney

UNITED STATES PATENT OFFICE.

RILEY E. ANTHONY, OF OMAHA, NEBRASKA.

ECCENTRIC HOOK.

Application filed April 13, 1922. Serial No. 552,086.

To all whom it may concern:

Be it known that I, RILEY E. ANTHONY, a citizen of the United States, residing at Omaha, in the county of Douglas and State 5 of Nebraska, have invented certain new and useful Improvements in Eccentric Hooks, of which the following is a specification.

The present invention relates to improvements in fasteners, and more particularly 10 that type adapted for use with screen doors, window screens, storm sashes and the like.

An object of the present invention is to provide a fastening device which may be adjusted so that the parts thereof may be 15 coupled together with comparative ease by hand and which may be subsequently adjusted or moved into such position as to draw the separable members together in relatively tight relation.

Another object of the invention is to provide a fastening device comprising a hook which may be secured to a screen door or the like and a keeper for the hook, the keeper being pivotally mounted on a door 20 frame or the like for riveting the hook and being pivoted so that it may be swung into a position for easily receiving the hook and may then be pressed into position for drawing the hook tight and for disposing the line 25 of draft through or beyond the pivotal center of the keeper for locking the hook when drawn taut.

The invention further aims at the provision of a fastener of this type which may be 30 economically manufactured, which comprises but relatively few parts, and which may be easily and quickly installed in different positions for use without exercising any particular skill.

With the foregoing and other objects in view, the invention will be more fully described hereinafter, and will be more particularly pointed out in the claims appended hereto.

In the drawings, wherein like symbols refer to like or corresponding parts throughout the several views.

Fig. 1 is a top plan view of a fastener constructed according to the present invention and as applied to a door and its frame, the door and frame being shown in horizontal section;

Fig. 2 is a side elevation of the fastener applied to the parts shown in Fig. 1, and 55 such parts being shown in section and fragmentarily;

Fig. 3 is a detail face view of the keeper member; and,

Fig. 4 is a top plan view thereof.

While the hook of this invention is adapted for use in practically all places where it is desired to couple and draw together into tight relation relatively movable members, the invention is shown as applied to a door 10, and its casing 11.

The fastener comprises a hook member and a keeper member, and the hook member is composed of a hook having a shank 12 with an eye 13 at its inner end hingedly mounted on the head 14 of a screw eye which is threaded into the inner side of the door 10. The screw eye 14 is so positioned that the hook 12 may be swung vertically so as to dispose the bill 15 of the hook face downwardly.

The keeper member comprises a flat body plate 16 having a pivotal opening 17 in one end and an arcuate slot 18 in spaced relation to and concentric with the pivotal opening 17, the slot 18 extending in a generally vertical direction. The other end of the keeper member is provided with a wing or thumb portion 19 which outstands in a plane at right angles to the plate 16 and which is adapted to be engaged by the fingers for swinging the plate 16 about its pivotal axis 17. The keeper member may be in the form of a casting, or may be made of sheet metal, in which latter event the thumb portion 17 is formed by bending up the opposite edges of the plate 16 and bringing such edges together into the position shown in Fig. 3 to form a relatively strong wing or thumb portion of double thickness.

The wing 19 is provided with a hook receiving opening 20 through which the bill 15 of the hook is adapted to engage.

The plate 16 is adapted to be positioned flat against the frame 11 of the door and is pivotally supported thereon by a screw 21 which freely passes through the opening 17 and is threaded into the door frame. The plate 16 is limited in its vertical or edge-wise swinging movements by a stop screw 22 which extends freely through the slot 18 and is threaded in the door frame 11.

The stop screw 22 is so located that the upper end of the slot engages the stop when the plate 16 is swung down into such position as to dispose the wing 19 in the horizontal plane of the pivot 21, or into a position below the plane of the pivot.

In use, the plate 16 is swung upwardly so as to move the wing 19 toward the door 10. The bill 15 of the hook is now inserted in the opening 20 of the wing and such operation may be easily effected owing to the slack condition of the fastener. The wing 19 is now pressed down into the position shown in Fig. 2. The downward movement of the wing carries with it the hook 15 and increases the distance between the wing and the screw eye 14, drawing the hook 12 taut and binding the door 10 against its casing 11. It is apparent that the device may be so adjusted as to effect the desired binding action and the door or other device will be held in place by the eccentric positioning of the wing 19 with respect to its axial support 21.

To open the door it is only necessary to lift the wing 19 to slacken the hook 12 when the latter may be quickly disengaged from the opening 20 and released from the keeper member.

I do not wish to be restricted to the size, form, and proportions of the various parts, and obviously changes could be made in the construction herein described without departing from the spirit of the invention, it being only necessary that such changes fall within the scope of the appended claims.

What is claimed is:

1. In a fastener for doors and the like the combination with a hook adapted to be carried by a door, a keeper plate having an opening therein for the reception of the bill of the hook, and a pivotal support for said keeper arranged eccentrically with respect to said opening whereby the keeper member may be swung on its pivotal support to move said opening toward and from the door for binding and releasing said hook.
2. In a fastener as specified, a hook adapted to be pivoted on one member, a keeper

adapted to be pivoted eccentrically on a second member and having a hook receiving portion with which the bill of the hook may be engaged, and a stop carried by said second member in the path of said keeper member for limiting the overthrow of the hook receiving portion thereof relatively to the pivotal support of the keeper member whereby to admit the drawing taut of said hook when engaged with the keeper member.

3. In a fastener as specified, a hook adapted to be pivotally supported upon a member, an elongated plate pivoted at one end to a second member and having an outstanding wing at its other end adapted to be engaged by the hand for swinging the keeper plate, said wing having a hook receiving opening therein and adapted to be swung into a position remote from the first member and beyond the pivotal support of the plate for drawing the hook taut and binding the members together, and a stop carried by the second member in the path of said plate for limiting the eccentric movement thereof.

4. In a fastener as specified, a hook adapted to be pivoted on one member, an elongated plate pivoted at one end to a second member and having an outstanding finger engaging the wing of its other end, said wing having an opening therein for receiving the bill of the hook and said wing being adapted to be positioned beyond the pivot of the plate remote from the first member, an arcuate slot in said plate concentric to the pivotal support thereof, and a stop carried by the second member engaging said slot for limiting the swinging of the plate.

In testimony whereof, I have affixed my signature in presence of two witnesses.

RILEY E. ANTHONY.
